UNITED STATES PATENT OFFICE

2,303,001

EXCAVATING APPARATUS

William Ruddock, South Pasadena, Calif., assignor of one-half to Marion P. McCaffrey, Los Angeles, Calif.

Application June 24, 1940, Serial No. 342,034

7 Claims. (Cl. 214—140)

This invention relates to an excavating apparatus, more particularly to the type commonly referred to as bulldozers and is an improvement of my co-pending application entitled Tractor shovel, bearing Serial No. 310,940, filed December 26, 1939, now Patent No. 2,260,539, granted October 28, 1941.

The object of the present invention is to provide an excavating apparatus so constructed that when the dipper is filled and raised it may be held in such position while moving the tractor to a discharge position.

Another object is to provide an excavating apparatus that may be readily operated as a bulldozer in which the tiltably mounted dipper may be adjusted and held at any desired angle when skimming over or leveling off the surface of the ground.

Other objects and advantages will be apparent from the following specification, reference being had to the accompanying drawings forming a part thereof in which:

Fig. 1 is a top plan view of a power shovel equipped with the improved apparatus.

Fig. 2 is a side elevation showing the dipper in lowered position.

Fig. 3 is a view similar to Fig. 1 showing the dipper in elevated position.

Fig. 4 is front elevation, parts being broken away and shown in section.

Fig. 5 is a fragmentary side elevation showing the dipper held in an adjusted position.

Fig. 6 is an enlarged section of the brake that holds the boom against vertical movement at different elevations.

Referring more specifically to the drawings, 10 designates a caterpillar tractor comprising side frame 11 and treads 12. Pivots mounted on the side frame rails as indicated at 14 are arms 15, the opposite or outer ends of which are secured to a supporting member 16 upon which is pivotally mounted as at 20 a dipper 18 of usual form.

Rigidly secured to the upper faces of the side rail frames 11 are a pair of frames 22 oppositely disposed which extend forwardly of the front end of the tractor and preferably consist of vertical and horizontal portions 23 and 24 respectively as clearly shown in Figs. 2 and 3 of the drawings.

Journalled in bearings 25 and 26 formed on the upper and lower ends of the frames 11 are cross shafts 27 and 28 respectively, and secured to the outer ends of shaft 27 are pulleys or drums 29 and to the outer ends of shaft 28 are pulleys or drums 30 over which extend cables 32 which serve

to hold the dipper in an elevated position as shown in Fig. 3, after the brake on shaft 27 has been applied in a manner hereinafter described.

The ends of the cables 32 are connected through sockets 33 to pins 34 projecting from the arms 15, passing under pulleys 30 and are wrapped in several coils around the pulleys 29.

Mounted on shaft 27 is a brake 31 consisting of a drum 32a in which is disposed a brake band 37 operated by a hydraulic cylinder 43 mounted on a plate 35 secured to a cross rail 36 extending between the vertically disposed portions 23 of the brackets 22.

Extending from cylinder 34 of the brake 31 is a tube 38 that leads to a cylinder 40 secured to the underside of the floor board 41 of the tractor, the piston of the cylinder being operated by a foot pedal 42 (see Fig. 2) when applying the brake. It will be understood that a mechanically operated brake may be employed in lieu thereof.

Connected to a bracket or the like 44 secured to the upper edge of the dipper 18 is a hoisting cable 45 that extends therefrom over pulleys 46 and 47 and is connected to the hoisting drum 48 which is driven by a shaft 49 inter-connected with the transmission of the tractor.

Pulleys 46 and 47 are rotatably supported by standards 50 and 51 secured to the cross rail 36 and floor board 41 respectively.

Rotation of the hoisting drum to raise the dipper is effected by engagement of a clutch (not shown) controlled by a foot pedal P', while the brake on the hoisting drum shaft is applied through a foot pedal P. It is understood that an automatic brake employed in power shovels to hold the dipper in elevated position may be employed if found desirable.

Pivots connected as at 54 to ears 55 secured to member 16 are links 56 having a plurality of notches 57 formed therein that are adapted to engage pins 58 projecting from the side walls of the dipper as shown in Fig. 5. These links serve to hold the dipper in adjusted position when it is desired to use the excavator as bulldozer to skim over or level the ground as clearly shown in Fig. 5.

In the operation of the apparatus after the dipper has received a load of material it is raised from the position shown in Fig. 2 to that shown in Fig. 3 through the medium of the hoisting drum 48 and cable 45, at which time the clutch of the hoisting drum shaft is engaged. The brake 31 on shaft 27 and that of the hoisting drum shaft are then simultaneously applied by depressing foot pedals 42 and P.

The clutch controlling rotation of the hoisting

drum to raise the dipper is released slightly before applying the aforesaid brakes by depressing foot pedal P. The tractor may then be driven to a convenient place for discharging the contents of the dipper. The hoisting drum brake is then released allowing the dipper to discharge its contents after which the brake 31 is gradually released allowing the dipper to be lowered to receive another load. The hoisting drum brake is then applied to hold the dipper against support 16 but is not completely applied to prevent its downward movement, and is held in braking engagement while loading the dipper to receive another load, the operation being then repeated.

While this invention has been described with particular reference to the specific form shown in the drawings, it is to be understood that such showing is for illustrative purposes only, and is not to be construed as imparting limitations upon the invention, which is best defined in the claims appended hereto.

I claim:

1. In combination with a tractor and operating means therefor, of a pair of arms pivotally secured to tractor frame, a dipper pivotally connected to said arms, a hoisting drum operable by the power mechanism of the tractor, a cable interconnected with said dipper and hoisting drum, pulley supporting frames secured to said tractor frame, a shaft rotatably mounted in said frames above said dipper, a second shaft rotatably mounted in the lower ends of said frames, a brake associated with one of said shafts for holding the dipper in an elevated position, pulleys secured to the outer ends of said shafts, and cables passing over said pulleys and connected to said arms, whereby when the dipper is raised by said hoisting drum and cable it will be held in elevated position when said brake is applied.

2. In combination with a tractor, a dipper supporting arm pivotally mounted on the tractor frame; a dipper pivoted to the supporting arm for movement from material carrying to material dumping position; a lifting cable connected to said dipper and operative to hoist the dipper carrying end of said arm and maintain the dipper out of dumping position; a pair of spaced rotatable drums secured to the tractor frame; cable means connected to the supporting arm and operatively connecting said rotatable drums; and brake means preventing movement of one of said rotatable drums, whereby slackening of the hoisting cable after application of said brake permits the dipper to pivot downwardly on the arm to dump the load.

3. In combination with a tractor, a dipper supporting arm pivotally mounted on the tractor frame; a dipper pivoted to the supporting arm so that its normal position is such as to dump a load; a lifting cable connected to said dipper to rotate it to load carrying position and lift said arm; an endless cable running over sheaves on the tractor frame and having one lay connected to the arm; and brake means preventing movement of said endless cable, to thereby hold the arm against movement in either direction, whereby slackening of the hoisting cable after application of said brake means will permit said dipper to pivot on the arm to dumping position.

4. In a material handling device, the combination of a tractor having a frame; an arm mount-

ed on said frame for movement to move one end of said arm in a substantially vertical direction; a dipper having a digging edge and mounted on said end of the arm with said edge facing away from said tractor frame, said dipper being movable with respect to said arm from material carrying to material dumping position; means exerting a force on said dipper in a direction to hold said dipper out of material dumping position and simultaneously raise the dipper carrying end of said arm; holding means for preventing vertical movement of said arm in either direction with respect to said tractor frame while said arm is in different adjusted positions, said dipper being so mounted that relaxation of said force when said arm is held against movement permits the dipper to move to a dumping position.

5. In a material handling device, the combination of a tractor having a frame; an arm mounted on said frame for movement to move one end of said arm in a substantially vertical direction; a dipper having a digging edge and mounted on said end of the arm with said edge facing away from said tractor frame, said dipper being movable with respect to said arm from material carrying to material dumping position; means exerting a force on said dipper in a direction to hold said dipper out of material dumping position and simultaneously raise the dipper carrying end of said arm; holding means including a brake for preventing vertical movement of said arm in either direction with respect to said tractor frame while said arm is in different adjusted positions, said dipper being so mounted that relaxation of said force when said arm is held against movement permits the dipper to move to a dumping position.

6. In a material handling device, the combination of a tractor having a frame; an arm mounted on said frame for movement to move one end of said arm in a substantially vertical direction; a dipper having a digging edge and mounted on said end of the arm with said edge facing away from said tractor frame, said dipper being movable with respect to said arm from material carrying to material dumping position; means for raising and lowering the dipper carrying end of said arm; and holding means for preventing vertical movement of said arm in either direction with respect to said tractor frame while the dipper is in different adjusted positions.

7. In combination with a tractor, a dipper supporting arm pivotally mounted on the tractor frame for movement to move the dipper carrying end of said arm in a substantially vertical direction; a dipper having a digging edge, and pivoted to the supporting arm with the digging edge facing away from said tractor frame, said dipper being mounted for movement from material carrying to material dumping position; a lifting cable connected to said dipper and operative to hoist the dipper carrying end of said arm and simultaneously maintain the dipper out of dumping position; and means including a brake for preventing vertical movement of said arm in either direction with respect to said tractor frame when the arm is in different positions, whereby slackening of the lifting cable during application of such brake means permits the dipper to pivot downwardly on the arm to dump the load.

WM. RUDDOCK.
